KIMBERLY STUART, OF NEENAH, WISCONSIN.

INDICATOR FOR BEATING-ENGINE ROLLS AND THE LIKE.

Application filed October 28, 1920. Serial No. 420,308.

To all whom it may concern:

Be it known that I, KIMBERLY STUART, a citizen of the United States; residing at Neenah, county of Winnebago, and State of Wisconsin, have invented certain new and useful Improvements in Indicators for Beating-Engine Rolls and the like, fully described and represented in the following specification and the accompanying drawings, forming a part of the same.

This invention relates to certain improvements in devices for indicating the operation of the beating or grinding elements in machines in which the material to be treated is passed between two co-operating elements which have a relative adjustment while the beating or grinding operation is progressing, such as the pulp beaters or grinders used in the manufacture of paper stock.

This class of machines usually include a stationary element such as a bed provided with grinding or beating bars or knives with which bed co-operates a grinding element as a roll provided with beating or grinding bars or knives. The stock to be treated is passed between these grinding or beating elements and is ground or beaten thereby. In the operation of these machines, it becomes necessary due to the change of stock as it is treated, or character of stock to be ground, or for other reasons, to effect a relative adjustment of these beating or grinding elements. This adjusting movement is a gradual one, and to effect the best results

this adjusting movement should be regular so that the action of the grinding elements on the stock is even and the stock all receives substantially the same amount of treatment. In this class of machines due to irregularities in the stock, as lumps of improperly disintegrated or digested wood or rags, for instance a sudden jump is given the roll which causes the roll to move suddenly with considerable of a shock, this being particularly the case in cold weather where lumps of frozen pulp may be present in the stock.

In paper mill practice when these beating or grinding machines are used for grinding or beating paper stock, their operation is watched by an operator who endeavors to regulate the grinding elements relatively to each other as regularly and evenly as pos-

sible, and to assist him in doing this various tell-tale or indicating devices have been suggested to show him whether he was regulating the machine evenly or not. These tell-tale or indicating devices as heretofore employed, did not take care of these jumps of the roll and did not, therefore, accurately indicate to the operator whether his machine was operating regularly or whether he was adjusting it regularly to the desired extent. Furthermore these tell-tale mechanisms are delicate and sudden large increases in pressure due to the jumps is liable to seriously injure them.

It is the especial object of the present invention to produce an indicating mechanism for machines of the character referred to, in which the shock or jump of the roll is taken care of, this jump being practically eliminated and only transmitted to the indicating mechanism in a slight degree so that the mechanism will operate evenly and apprise the operator as to whether his machine is working regularly and as to whether his adjustment thereof is of the required regularity and evenness, and so that the indicating mechanism will not be injured by such sudden increases in pressure.

A further object of the invention is to produce such an indicating mechanism which may be easily and readily installed with any machine of the type referred to, and which shall be simple, durable and accurate in its action.

A further object of the invention is to produce an improved indicating mechanism for use in connection with the mechanism for avoiding the shock or jump, which may be provided with a standard scale for the particular grade of material being treated so that the operator may regulate the machine to cause the indicating mechanism to follow this standard scale as closely as possible and so get the best results, and to produce a record of each run of the machine which is permanent, irregularities in the scale notifying the operator that his manipulation of the machine is irregular, or that the stock is lumpy and not properly prepared before going into the beater.

With these and other objects not specifically referred to, the invention consists in

2
certain novel combinations and parts which will be fully described in connection with the accompanying drawings and then specifically pointed out in the claims annexed hereto.

In the drawings:—

Figure 1 is a side elevation of so much of a pulp beating engine embodying the invention as is necessary for an understanding 10 thereof.

Figure 2 is a plan view, partly broken away of a part of the indicating mechanism;

Figure 3 is a sectional side elevation, 15 partly broken away showing the mechanism for operating the indicator in section, the section being taken on line 3—3 of Fig. 2; and

Figure 4 is a partial side view of a modified construction embodying the invention 20 which may be used.

Referring now to these drawings, the invention has been illustrated as embodied in what is known as a beating engine in which pulp stock is beaten and disintegrated to 25 form the stock used in the manufacture of paper, though it will be understood that the invention is intended to be and can be employed in other types of machines having co-operating beating or grinding elements 30 adjustable relatively to each other during the progress of the grinding or beating operation.

The particular machine illustrated includes a grinding element as a beater roll 1, 35 provided with the usual knives 2, this beater roll being mounted to rotate in a beater tub 1' in which is a co-operating grinding element as bed plate 2', illustrated in dotted lines in Fig. 1. This beater roll is mounted 40 on a shaft 3 supported in bearings 4 carried by a movable cradle 5, one of these cradles being provided at each end of the machine and supported from four standards 6, two of which are shown. This roll has a vertical 45 movement so that it may be raised or lowered relatively to the bed plate as required, it being raised to its maximum at the beginning of a beating operation and gradually lowered as the beating operation progresses. 50 This adjustment may be effected in any usual manner, as by moving the cradles 5 through a gear and shaft connection, not illustrated, by means of an adjusting wheel 7, as is customary in this class of machines.

55 In accordance with the invention, mechanism is provided for indicating the downward movement of the roll and for taking care of any jump caused by irregularity of the stock, so that this jump is sufficiently reduced to permit irregularities to be indicated, and prevent injury to the indicating mechanism. While this mechanism may be varied widely in construction, it will include 60 fluid pressure actuated connections between the roll and the indicating mechanism, these

connections being of such a character as to transmit the downward movement of the roll to the indicating mechanism and to lessen or absorb the shock due to the jumping of the roll. As illustrated, air pressure 70 is utilized for effecting this, although if desired under certain circumstances, water or other fluid pressure may be employed.

In the particular construction illustrated, referring first to Figs. 1 to 3, there is provided a cylinder 8 in which works a piston 9. This cylinder is firmly secured in position, as by being supported on a base 10 rising from the floor. The piston 9 is provided with a stem or rod 11, which is secured as 75 by a plate 12 to the underside of one of the cradles 5, before referred to, and partakes of the movement of the cradle.

In the best constructions the connections by which the regulator is secured in operative connection with bearings of the beater roll will include adjusting devices so that when the parts are assembled they may be adjusted to the required position, as for instance, if the concrete base such as 10, may be made a little too high, and any play due to wear in use can be taken care of. While these adjusting devices may be of various characters, where the piston rod 11 is directly connected to the lighter bar, and as 80 shown in Figs. 1 and 2, the rod is arranged so that it can be adjusted to the required extent relatively to the bar. As shown, the end of the piston rod 11 is threaded, as indicated at 11' and this threaded end extends 90 into an internally threaded hole 11'' passing through the plate 12, the rod being adjustably secured in position by a lock nut 12'. With this construction the piston rod and piston may be turned in the cylinder to 100 adjust the parts as desired, sufficient space being left above the piston to provide for 105 such adjustment which, in the majority of cases, is very slight.

Air under pressure, if air is the pressure 110 medium employed, from a suitable source not shown is admitted through a pipe 13 to the lower portion of the cylinder 8, the admission of the air being controlled by a valve 14, and, to enable the proper pressure 115 to be determined, a pressure gauge 15 is connected to the pipe 13 through a pipe 16 located between the cylinder and the valve 14.

This cylinder connects with an indicating 120 mechanism which preferably is of such character as to provide a permanent record of the operation of the roll. While this mechanism may be of various characters there is provided a frame 17 in which may be mounted 125 a mechanism actuated by compressed air, such as a dry air flow meter, provided with removable indicating record surface, such as a disc, indicated by the numeral 18, the record being drawn on the record disc by 130

means of the usual ink needle 19. This indicating mechanism is of a well known type, and need not be further described, as its specific mechanism is unnecessary for an understanding of the invention. In the best constructions, however, a removable record disc 18 will be provided with what may be termed a standard guide line indicated by the numeral 20, the operator endeavoring to so regulate the machine as to cause the indicating needle 19 to follow closely this standard guide line which should be the course indicated by the needle when the machine is operating properly.

15 This indicating mechanism may be supported and connected to the pressure cylinder in any suitable manner, and the cylinder, if desired, may be directly connected therewith, the compressibility of the air in the cylinder absorbing to a large extent the shocks caused by the jumping of the roll so that the action of the indicator is fairly regulated. In the best constructions, however, the pressure cylinder will be connected 25 with the air pressure meter or gauge through a second cylinder interposed between the pressure cylinder and gauge, this second cylinder being directly connected with the gauge and helping to absorb any sudden increase of pressure in the first cylinder so that jar and shock caused by the jumping of the roll is practically eliminated and the pressure transmitted to the gauge is very even and regular. While various constructions 30 may be provided for effecting this, in the construction illustrated there is provided a second or auxiliary cylinder 21 which, if desired, may be cast integrally with the main cylinder 8. A pipe 22 having a reducing valve 23 therein connects the main cylinder 8 from near its bottom to the bottom of the auxiliary cylinder 21 and a small outlet pipe 24 connects the top of the auxiliary cylinder 21 to the pressure indicating 35 gauge.

In the best construction and particularly in an apparatus used in the winter time or cold weather where there is liable to be lumps of frozen pulp passing through the 40 beating or grinding machine and thus cause a greater irregularity in the pressure transmitted to the cylinder, a reducing diaphragm or baffle 25 may be employed, this diaphragm being secured in any suitable 45 manner in the auxiliary cylinder 21, this diaphragm together with the reducing valve 23 still further reducing the shocks coming from the sudden compression or expansion of the air in the cylinder 1. If desired, an 50 exhaust valve 26 may be provided anywhere in the line, as in the pipe 24 for reducing the pressure after the grinding operation has stopped and the machine is being emptied of or charged with the material that is 55 treated thereby.

The operation of the device will be clear from this description, but may be briefly indicated as follows:—

When the machine is operated to beat or grind a charge of material the beater roll is 70 raised to its maximum high position with respect to the bed. As the beater roll is thus raised the piston in the cylinder 8 is raised toward the top of the cylinder. The parts are dimensioned so that when the piston is lifted by lifting the roll cradles the piston is not drawn to the top of the cylinder but a space is left, as indicated in Fig. 3 to allow jumping of the roll when at its maximum high adjusted position. After the 80 piston has been raised to the required position the air valve 14 is opened and air under pressure is admitted to the cylinder until the pressure gauge indicates the pressure desired to be maintained in the cylinder which may vary as desired depending on the type of the machine with which the apparatus is to be used. When the pressure has reached the desired degree the valve is then closed and the beating operation begun. As this operation 85 progresses the roll is lowered toward the bed plate by the operator through the hand wheel 7 and operating mechanism actuated thereby, and this lowering compresses the air in the cylinder 8. This increase of 90 pressure is transmitted from the cylinder 8 through the reduction valve 23 to the cylinder 21 and thence through the outlet pipe 24 to the record gauge and an ink line record is made on the gauge recording the 100 progress of the roll, it being understood that valve 26 is closed. After the run is completed the beater is emptied and the operator may release the pressure through the valve 26 and the operation is then repeated, a fresh 105 disc 18 being placed in the gauge frame 17 for the next run.

It frequently happens, especially with machines already constructed, that the lighter bars that support the beating roll 110 come too close to the floor or other support on which the beating engine is erected to permit the insertion of the regulator between the lighter bars and such support. It further happens that in some types of 115 machine the adjustment made during the beating operation is so slight that on account of the small movement of the piston a satisfactory record is difficult to obtain, and it becomes desirable to increase the movement of the piston so as to get a movement sufficient to produce a satisfactory record. I have devised a construction for meeting these requirements which is a modification 120 of the construction heretofore described, and this modified form is shown in Fig. 4. As there illustrated, the piston is not directly connected with the lighter bars of the engine which support the beating roll, but the cylinder and the piston may be arranged at any 125 130

desired point adjacent the engine, being connected with the lighter bar through suitable connections which will operate the piston by the movement of the lighter bars, 5 and these connections will preferably include the means employed for increasing the movement of the piston. While these connections may be widely varied, and while various mechanisms may be employed for effecting 10 the increase in the movement of the piston, a convenient one is that shown, in which there is provided a rod 28 connected to the lighter bar through the medium of the plate 12, this connection being preferably the adjusting connection heretofore described. 15 This rod 28 connects through a loose connection 29 with a short arm 30 of a multiplying lever pivoted at 31 in a suitable standard 32 rising from the floor or other 20 suitable support. The long arm 33 of this lever is connected through a loose connection 34 and a coupling 35 with the threaded end 36 of the piston rod 37, this construction being employed so that there may be a 25 slight adjustment of the piston to take care of any play occasioned by wear, etc. The piston rod 37 carries a piston 38 working in a cylinder 39 and a pipe connection 40 leads to the indicating mechanism, the movement of the piston in the cylinder causing 30 a record to be made on the indicating dial.

The pipe 40 may lead directly from the top of the cylinder to the indicating mechanism, in which case a reducing valve, similar to valve 23 before referred to, is inserted 35 in this pipe in any convenient place between the cylinder and the indicating device. Such construction is ordinarily sufficient where the adjustment of the roll is slight and the 40 movement of the piston has to be increased to effect a satisfactory record. It may be desirable, however, to employ an auxiliary cylinder like the cylinder 21, heretofore referred to, and such a cylinder is shown 45 marked 41 mounted directly on the cylinder 39, and this cylinder may be provided with a removable pressure reducing diaphragm, like the diaphragm 25 before referred to, and having the same functions. When this 50 construction is employed the pipe 40 leading to the indicating mechanism is connected with the auxiliary cylinder 41.

Air is supplied to the cylinder 39 above the piston through pipe connections similar 55 to those heretofore referred to, and the cylinder 39 above the piston is connected with the cylinder 41 through a pipe connection 42 provided with a reducing valve 43.

With this construction a very slight movement of the lighter bar may be increased 60 at the piston so as to cause the piston to have a sufficiently increased movement relatively to the movement of the bar as to produce a satisfactory record, the amount of increase 65 in the movement being determined by the

relative lengths of the arms 30 and 33 of the multiplying lever, as will be readily understood, these arms being proportioned to produce the movement required. Furthermore, with this construction the regulator may be 70 positioned at any desired point adjacent the beating engine and does not have to be in the space between the lever bars and the floor, which in some instances is very cramped.

The operation of the device is the same as 75 that already described and need not be referred to again.

With this regulator the mill superintendent may have a permanent record of each run of the machine and can determine 80 whether the operators are adjusting the roll relatively to the bed with the desired regularity. Furthermore by the use of a disc having a standard gauge line the operator regulates his adjusting mechanism so as to 85 cause the indicator needle to follow this line as closely as possible and thus keep the machine operating to the regular standard given him. Furthermore the operator can tell whether he is manipulating the machine 90 properly, or whether irregularities in operation are due to badly prepared stock.

While the invention has been shown and described in its preferred form, it will be understood that changes and variations may 95 be made in the mechanism whereby the results aimed at may be effected and that mechanisms operated by fluid pressure other than air may be employed if desired, and that the invention may be employed with 100 beating or grinding machines of various types.

What is claimed is:

1. The combination with beating or grinding elements, of means for effecting 105 a relative adjusting of the elements, an indicating device, and fluid pressure operated means connected with one of the elements for causing the indicating device to evenly indicate the movement of the adjusted element.

2. The combination with beating or grinding elements, of means for effecting a relative adjustment thereof, an indicating device, and air pressure actuating means 115 connected with one of the elements for causing the indicating device to evenly indicate the movement of the adjusted element.

3. The combination with beating or grinding elements, of means for effecting 120 a relative adjustment thereof, an indicating device, a cylinder, a piston therein connected with one of the elements, means for admitting fluid under pressure to the cylinder, and connections between the cylinder and the indicating device for operating the latter.

4. The combination with beating or grinding elements, of means for effecting 125 a relative adjustment thereof, an indicating 130

device, a cylinder, a piston therein connected with one of the elements, means for admitting air under pressure to the cylinder and connections from the cylinder to the indicating device for operating the latter.

5. The combination with beating or grinding elements, of means for effecting a relative adjustment thereof, an indicating device, a cylinder, a piston therein connected with one of the elements, means for admitting air under pressure to the cylinder, connections from the cylinder to the indicating device for operating the latter, and pressure reducing means in the connections.

10. The combination with beating or grinding elements, of means for effecting a relative adjustment thereof, an indicating device, fluid pressure operated means connected with one of the elements for actuating the indicating device, and pressure reducing means between the fluid pressure operated means and the indicating device.

15. The combination with beating or grinding elements, of means for effecting a relative adjustment thereof, an indicating device, a cylinder, a piston therein connected with one of the elements, means for admitting air under pressure to the cylinder, a second cylinder, connections between the cylinders, and connections between the second cylinder and the indicating device.

20. The combination with beating or grinding elements, of means for effecting a relative adjustment thereof, an indicating device, a cylinder, connections between the cylinder and one of the elements, connections from the cylinder to the indicating device, means for admitting fluid under pressure to the cylinder, and pressure reducing means in the cylinder.

25. The combination with beating or grinding elements, of means for effecting a relative adjustment thereof, an indicating device, a cylinder, connections between the cylinder and one of the elements, connections from the cylinder to the indicating device, means for admitting fluid under pressure to the cylinder, and a perforated plate in the cylinder for reducing the pressure transmitted to the indicating device.

30. The combination with beating or grinding elements, of means for effecting a relative adjustment thereof, an indicating device, a cylinder, a piston therein, connected with one of the elements, means for admitting air under pressure to the cylinder, a second cylinder, connections between the second cylinder and the indicating device, and pressure reducing means in the second cylinder.

35. The combination with beating or grinding elements, of means for effecting a relative adjustment of the elements, an indicating device, fluid pressure operated means connected with one of the elements by

device, a cylinder, a piston therein, connected with one of the elements, means for admitting air under pressure to the cylinder, a second cylinder, connections between the cylinders including a pressure reducing device, connections between the second cylinder and the indicating device, and pressure reducing means in the second cylinder.

40. The combination with beating or grinding elements, of means for effecting a relative adjustment thereof, an indicating device, a cylinder, a piston therein connected with one of the elements, means for admitting air under pressure to the cylinder, a second cylinder, connections between the cylinders including a reducing valve, connections between the second cylinder and the indicating device, and a perforated plate in the second cylinder.

45. The combination with beating or grinding elements, of means for effecting a relative adjustment thereof, an indicating device including a removable dial and means for producing a record thereon, and fluid pressure operating means connected with one of the elements for causing the movement of the adjusted element to be recorded on the dial.

50. The combination with a beating roll, of an adjustable bearing therefor, a cylinder, a piston operating therein and connected with the bearing and partaking of the movement thereof, means for admitting fluid under pressure below the piston, an indicating device, and connections from the cylinder below the piston to the indicating device for operating the latter.

55. The combination with a beating roll, of an adjustable bearing therefor, a cylinder, a piston operating in the cylinder connected with the bearing and partaking of the movement thereof, means for admitting air under pressure to the cylinder below the piston, a second cylinder, pipe connections having a reducing valve between the cylinders and indicating device, and pipe connections from the second cylinder to the indicating device for operating the latter.

60. The combination with a beating roll, of an adjustable bearing therefor, a cylinder, a piston therein connected with the bearing, and working in the cylinder, means for admitting air under pressure to the cylinder below the piston, a second cylinder, pipe connections including a reducing valve between the cylinders, a removable perforated plate in the second cylinder, an indicating device, and pipe connections from the second cylinder to the indicating device for operating the latter.

65. The combination with beating or grinding elements, of means for effecting a relative adjustment of the elements, an indicating device, fluid pressure operated means connected with one of the elements by

- the movement of which the indicating device is caused to evenly indicate the movement of the adjusted element, and means for increasing the movement of the fluid pressure operating means.
18. The combination with beating or grinding elements, of means for effecting a relative adjustment thereof, an indicating device, air pressure actuating means connected with one of the elements by the movement of which the indicating device is caused to evenly indicate the movement of the adjusted elements, and means for increasing the movement of the air pressure actuating means.
19. The combination with beating or grinding elements, of means for effecting a relative adjustment thereof, an indicating device, a cylinder, a piston therein, connections including a multiplying lever between the piston and one of the elements, means for admitting fluid under pressure to the cylinder, and connections between the cylinder and the indicating device for operating the latter.
20. The combination with beating or grinding elements, of means for effecting a relative adjustment thereof, an indicating device, a cylinder, a piston therein, connections including a multiplying lever between the piston and one of the elements, means for admitting air under pressure in the cylinder, and connections from the cylinder to the indicating device for operating the latter.
21. The combination with beating or
- grinding elements, of means for effecting a relative adjustment thereof, an indicating device, a cylinder, a piston therein, connections between the piston and one of the elements, said connections including means for adjusting the position of the piston, means for admitting air under pressure to the cylinder, and connections from the cylinder to the indicating device for operating the latter.
22. The combination with beating or grinding elements, of means for effecting a relative adjustment thereof, an indicating device, a cylinder, a piston therein, a multiplying lever between the piston and one of the elements for increasing the movement of the piston, adjustable connections between the lever and one of the elements, means for admitting air under pressure to the cylinder, and connections from the cylinder to the indicating device for operating the latter.
23. The combination with a beating roll and co-operating bed, of bearings for the roll, a rod connected to one of the bearings, a multiplying lever connected to the rod, a cylinder, a piston therein connected to the other end of the lever, adjustable connections between the rod and the bearings, an indicating device, means for supplying air under pressure to the cylinder, and connections from the cylinder to the indicating device.

In testimony whereof, I have hereunto set my hand.

KIMBERLY STUART.
